UNITED STATES PATENT OFFICE.

LOUIS G. STRNAD, OF CHICAGO, ILLINOIS.

DESIGN FOR A CURTAIN-ROD HOLDER.

57,740.

Specification for Design.

Patented Apr. 26, 1921.

Application filed August 11, 1920. Serial No. 402,907. Term of patent 7 years.

To all whom it may concern:

Be it known that I, LOUIS G. STRNAD, a citizen of the Republic of Czecho-Slovakia, residing at Chicago, in the county of Cook and State of Illinois, have invented a new, original, and ornamental Design for a Curtain-Rod Holder, of which the following is a specification, reference being had to the accompanying drawing, forming part thereof.

I claim:

The ornamental design for a curtain rod holder as shown.

LOUIS G. STRNAD.
